(57) **CLAIM**

The ornamental design for a wheel for a automobile, as shown and described.

DESCRIPTION

FIG. 1 is a front view of a wheel for an automobile showing my new design;

FIG. 2 is a rear view thereof;

FIG. 3 is a left side view thereof;

FIG. 4 is a right side view thereof;

FIG. 5 is a top plan view thereof;

FIG. 6 is a bottom plan view thereof;

FIG. 7 is a first perspective view thereof;

FIG. 8 is a second perspective view thereof; and,

FIG. 9 is a partially enlarged third perspective view thereof. The claim is shown in full-tone shading. Elements shown in half-tone shading form no part of the claimed design.

1 Claim, 9 Drawing Sheets
